(57) **CLAIM**

The ornamental design for a table having an electrically elevatable lift having a lazy-susan platform for supporting a microwave oven, as shown and described.

DESCRIPTION

FIG. 1 is a perspective view of table having an electrically elevatable lift having a lazy-susan platform for supporting a microwave oven, embodying the design of the present invention, showing the lift in an elevated position; the broken line showing of environmental window structure is for illustrative purposes only and forms no part of the claimed design.

FIG. 2 is a front elevational view thereof;

FIG. 3 is a rear elevational view thereof;

FIG. 4 is a left side elevational view thereof, the right side elevational view being a mirror image thereof;

FIG. 5 is a top plan view thereof; and,

FIG. 6 is a bottom plan view thereof.
